CLAIM

The ornamental design for a Display Box, as shown and described.

DESCRIPTION

FIG. 1 is a front perspective view of a display box showing my new design;

FIG. 2 is a front elevation view thereof;

FIG. 3 is a top plan view thereof;

FIG. 4 is a left side elevation view thereof;

FIG. 5 is right side elevation view thereof;

FIG. 6 is a bottom plan view thereof;

FIG. 7 is a rear elevation view thereof;

FIG. 8 is a front perspective view of the display box, showing my new design in an open configuration;

FIG. 9 is a front elevation view thereof;

FIG. 10 is a top plan view thereof;

FIG. 11 is a right side elevation view thereof;

FIG. 12 is a left side elevation view thereof;

FIG. 13 is a bottom plan view thereof;

FIG. 14 is a rear elevation view thereof.

The elements shown in the dash-dot-dash lines present on the surface of the article depict a wood grain pattern which does not form part of the claimed design. The elements shown in the evenly spaced broken lines depict environmental elements which do not form part of the claimed design.

1 Claim, 8 Drawing Sheets
